UNITED STATES PATENT OFFICE.

JOHN F. McCANNA, OF CHICAGO, ILLINOIS, ASSIGNOR TO IMPERIAL BRASS MANUFACTURING COMPANY, OF CHICAGO, ILLINOIS, A CORPORATION OF ILLINOIS.

FORCE-FEED LUBRICATOR.

1,107,220.

Specification of Letters Patent. Patented Aug. 11, 1914.

Application filed August 26, 1912. Serial No. 716,980.

To all whom it may concern:

Be it known that I, JOHN F. McCANNA, a citizen of the United States, and resident of the city of Chicago, in the county of 5 Cook and State of Illinois, have invented certain new and useful Improvements in Force-Feed Lubricators, of which the following is a full, clear, and exact specification.

10 This invention relates to improvements in force feed lubricators in which a portion of the mechanism for supplying oil from the reservoir and forcing it onward to its lubricating destination is projected from 15 the reservoir and therefore liable to injury, and in which two or more pumps have necessarily been used in forcing the oil from the reservoir onward to its destination.

The prime object of this invention is a 20 force feed lubricator the mechanism of which is entirely confined within the reservoir, the oil from which is alternately supplied through separated passages to a single piston pump and likewise forced therefrom 25 through lubricating pipes onward to its destination.

A further object of this invention is to 30 make it possible and practical to utilize a single rotary valve as a means of connection between the oil reservoir and a single piston pump, and between the discharge pipe leading from the pump and valve for conducting oil to its lubricating destination which valve during a continuous revolution 35 provides for alternately supplying from the reservoir to the pump through separate passages and likewise forced by the pump through lubricating pipes onward to its destination.

40 Another object of this invention is to have the pump piston provided with means for adjusting its length of stroke for varying the feed of the oil to the pump and likewise from the pump to its lubricating destination 45 provided with adjustable means which may be conveniently locked by a simple and effective means against the possibility of accidental movement.

With said ends in view my invention finds 50 embodiment in certain features of novelty and construction, combination and arrangement of parts by which the said object and certain other objects are hereinafter attained, all as fully described with reference

to the accompanying drawings and more particularly pointed out in the claims.

In said drawings Figure 1 illustrates a side view partly in section of a force feed lubricator in which my invention finds embodiment; Fig. 2 is a vertical section on the line 2—2 of Fig. 1 looking in the direction indicated by the arrows; Fig. 3 is a transverse section on the line 3—3 of Fig. 2 looking in the direction indicated by the arrows; Fig. 4 is a detail transverse section on the line 4—4 of Fig. 2; Fig. 5 is a detail vertical section of the adjustable nut of the upper end of the piston and the locking nut for adjusting the stroke of the same; Fig. 6 is a perspective view of one of the rotary valves; Fig. 7 is a perspective view of the key for the adjustable nut shown in Fig. 5, and Fig. 8 is a transverse section on the line 7—7 of Fig. 5 looking in the direction indicated by the arrow.

Similar characters of reference indicate same parts in the several figures of the drawing.

As a means of support for the several parts of the lubricator structure I may employ two separated metal brackets 8 and 9 connected for the purpose of rigidity by a tie rod 10 and supported upon the bottom of the oil reservoir 11. The upper end of the reservoir is provided with an inturned flange 12 upon which is mounted an annular plate 13 in turn supporting an annular plate 14 provided at its inner edge with an upwardly inclined flange 15 between which and the plate 13 is secured a pane of somewhat 85 thick glass 16, the cover so formed being secured to the reservoir by means of screws 17 passing through the annular plates 13 and 14 and screwed into the flange 12. The reservoir is also provided with a single opening 18 for an elbow 19, the inner end 20 of which is screw-threaded to receive a nut 21 for connecting the lubricating pipe herein-after described, and also (see Fig. 2) with an opening 22 through which to project a power shaft 23 journaled in the brackets 8 and 9. The power shaft 23 has upon its inner end a pinion 24 meshing with a gear wheel 25 upon a shaft 26 journaled in the brackets 8 and 9 and prevented from endwise movement by a collar 27 at one end secured to the shaft by a pin 28 bearing against a hub 29, and the bearing of the

gear 25 against the hub 30 on the brackets 8 and 9, the pinion and the gear preferably being a two to one gear.

5   Mounted upon and rotating with a shaft
26 is a cone-shaped valve 32, of which there
may be two or more, which valve is splined
on the shaft so that it may be tightened in
its bearing against a valve casing 33, sep-
arate from the brackets 8 and 9, by means
10 of a coiled spring 34 one end of which bears
against a shoulder 35 formed in the casing,
and the other end against an opposing
shoulder 36 on the end of the valve. Valve
32 is provided with two peripheral grooves
15 37, 38, one of which 37 is well toward the
apex of the cone formed by the valve, and
the other 38 toward its base between the ends
of which and longitudinal of the valve the
periphery thereof is uninterrupted in its
20 bearing against the casing as indicated at
39—39 in Fig. 1. The groove 37 (see Fig.
4) is adapted to form a connection by means
of a pipe 38 with the oil in the reservoir well
toward its bottom and an oil inlet 39^a in a
25 pump 40 on the upstroke of its piston 41,
and also through the oil inlet 39^a with a lu-
bricating pipe 42 on the downstroke of the
pump piston alternately with the rotation of
30 the valve the oil from the reservoir being
cut off when the pump is in connection with
the lubricating pipe 42, and vice versa. On
the upstroke of the pump (see Figs. 2 and
3) and during the revolution of the valve
35 the groove 38 connects the reservoir with
the pump by means of a pipe 43 and an inlet
45 in the pump and also said inlet 45 with a
lubricating pipe 46. In short, during a con-
tinuous revolution of the valve and on al-
ternate upstrokes of the piston, both of said
40 grooves successively connect the oil reser-
voir with the pump and on the downstroke
of the piston, likewise connect the pump
with their respective lubricating pipes and
whereby it is made possible and practical
45 to use a single rotating valve and a single
piston pump coöperating therewith to sup-
ply oil from the reservoir to the device to
be lubricated in a lubricator in which four
50 strokes of the piston are required to conduct
oil from a reservoir onward to its lubricat-
ing destination automatically through two
passages from the pump.

The pump piston is actuated by means of an eccentric 47 on the power shaft 23 from the strap 48 of which eccentric projects an arm 49 in the free end of which arm is mounted a lever 50 on a pivot 51 about midway length of the lever. One end of lever 50 is mounted upon a pivot 52 sustained by posts 53—53 projecting upwardly from the brackets 8 and 9 the free end of the lever 50 being provided with a bifurcation 54 sleeved upon the stem 55 of the piston 41, which (see Fig. 2) is cut away or flattened 60 at both sides as shown at 56 for the engage-

ment therewith of the lever yoke, and also to form shoulders at a point 57 limiting the downward movement of the piston and thereby preventing the piston from being carried downwardly by the lever to a ham- 70 mering contact with the bottom of its cylinder.

Above the cut away portion 56 of the piston stem is a flange 58 of greater diameter than that of the screw-threaded end 59 of the stem adjustable upon which is a nut 60 provided with a depending hub 61 bearing against the flange 58, the function of which nut is to adjust the screw of the piston and thereby vary the supply of oil to and its discharge from the pump onward to its destination. If, for example, the nut is raised on the stem above the position shown in Figs. 1 and 2, there will be lost motion between the lever and the nut and the stroke of the piston be correspondingly shortened, and on the other hand lengthened when the nut is moved to a lower position than it is shown in the drawings to occupy relative to the free end of the lever 50, the shoulder 57 on the piston forming a means whereby on the downstroke of the lever the piston is moved in the same direction and by this means the amount of oil supplied to and discharged from the pump through the rotary valve may be determined and fixed.

As a novel and convenient means for positively locking the nut in its several adjustments the stem of the piston rod (see Figs. 5, 7 and 8) is provided with an elongated longitudinal slot 62 extending well toward the base of the screw-threaded portion of the stem the nut being also provided with a similar but shorter slot 63 adapted to be registered with the slot 62 in the stem for the reception of a V-shaped key 64 adapted to be passed through these two slots when in register with each other and held against longitudinal movement by means of lugs 65 near their free ends adapted to engage with opposing longitudinal grooves 66 for preventing the accidental longitudinal displacement of the key with the nut 60 and so that the key without disconnecting it from the piston stem may be raised above the nut for adjusting it and thereupon lowered to its locking position.

As a means for preventing accidental disengagement of the key from the nut the latter may be provided at one side adjacent the lock 65 with a perforation 67 through which and other registering perforations 68 in the key a pin may be passed and thereby the key be prevented from accidental rising to disengagement with the nut. 125

The key 64 is perfectly V-shaped and of spring steel not only for the purpose of cheapness in construction, ease of manipulation, accessibility for adjustment and permanency of locking but because by its resili- 130

ency a frictional contact is produced between it, the nut and the stem, to prevent its accidental movement when once adjusted to its operative position.

5 Having described my invention, what I desire to secure by Letters Patent is:

1. A force feed lubricator comprising in combination a single piston pump, separate passages leading from the reservoir to the 10 pump and two separate passages leading from the pump to lubricating pipes through which the oil is conducted to its destination and a rotary valve providing separate passages each of which during the rotation of 15 the valve alternately connect the pump with the reservoir and with a lubricating pipe, all of said mechanism being entirely confined within the reservoir.

2. A force feed lubricator comprising in 20 combination a single piston pump, separate passages leading from the reservoir to the pump and two separate passages leading from the pump to lubricating pipes through which the oil is conducted to its destination, 25 a rotary valve providing separate passages each of which during the rotation of the valve alternately connect the pump with the reservoir and with the lubricating pipe all of said mechanism being entirely confined 30 within the reservoir said reservoir being pro-

vided in its top with a glass window forming a portion of the walls thereof.

3. A force feed lubricator comprising in combination a single piston pump, two separate supply and a plurality of discharge 35 pipes therefor, a rotating valve interposed between said pump and passages provided with peripheral grooves separately connecting therewith two passages in the pump, one of which is common to each of the valve 40 grooves whereby oil is supplied to and discharged from the pump through one passage therein during the rotation of the valve.

4. A force feed lubricator comprising in combination a reservoir, a power shaft, a 45 single piston pump and eccentric on said shaft connected with the piston, means on the piston for adjusting the stroke thereof, a rotary valve provided with separate grooves forming a plurality of oil passages 50 connecting the contents of the reservoir with the pump and discharge passages conducting the oil onward to its destination.

In witness whereof, I have hereunto set my hand and affixed my seal, this twenty- 55 third day of August A. D. 1912.

JOHN F. McCANNA. [L.S.]
